MINING MACHINE

Ernst F. Muller, Columbus, Ohio, assignor to The Jeffrey Manufacturing Company, Columbus, Ohio, a corporation of Ohio

Application May 29, 1930. Serial No. 457,327

2 Claims. (Cl. 262—28)

The present invention relates particularly to mining machines of the so-called "Arcwall" type wherein a turntable is mounted at the forward end of a truck for rotation about a substantially vertical axis and has mounted thereon an elongated cutter bar which is adapted to engage a coal face in front of the machine in the well-known manner to form an arcuate cut or which may be positioned in laterally projecting relation to the machine to form a "longwall" cut.

Machines of this general type have long been in use and the mounting means provided for the turntable has heretofore been sufficiently adequate. With the development of the machine as at present, however, due to the greater weight which the turntable is called upon to support, much of which projects beyond the bounds of the turntable and thus exerts a distortive effect thereon. It has been found that there is a disproportionate loss of power due to friction.

The well-known "Jeffrey Arcwall" machine of the prior art, for example, comprises a wheel mounted truck provided forwardly with three vertically extensible and retractable pedestals which support a ring upon which the turntable is mounted. The ring has mounted thereon on radial axes a number of rollers which engage the lower surface of the turntable to support the latter for rotation about a substantially vertical axis. Supported beneath the turntable for rotation about axes perpendicular to the turntable surface are a number of rollers which engage the inner face of the ring to prevent displacement of the turntable in the radial direction of the ring. Further, depending from the lower turntable margins are a number of brackets having angular portions extending under and adapted to engage the lower face of the ring to prevent tilting of the turntable relative to the ring. In practice these various mounting instrumentalities develop large frictional resistance and for this reason impair the general efficiency of the machine.

According to the present invention I provide novel anti-friction mounting means for the turntable whereby its turning resistance is reduced to a minimum.

In the accompanying drawing I have shown a preferred embodiment of the invention, although it will be understood that I do not restrict myself to this illustrative showing.

In the drawing:

Figure 1 is a plan view of a "Jeffrey Arcwall" machine provided with anti-friction turntable supporting means in accordance with the present invention.

Figure 2 is a section on line 2—2 of Figure 1, and

Figure 3 illustrates a detail.

Referring to the drawing, reference numeral 5

designates generally a wheel mounted truck adapted to be positioned on a mine track to be propelled thereover by self-contained motive devices. Mounted on three upright pedestals 6 is a ring 7, Figure 2, which is normally supported in horizontal position in which it may be raised or lowered by equal extension or retraction of the pedestals, or, if desired, it may be tilted by differential extension and retraction of the pedestals.

Reference numeral 11 designates the turntable whose margins overlie the upper face of ring 7. The upper face of the ring and the lower marginal portion of the turntable are provided with opposed grooves 8 and 12, respectively, developed on equal radii about the ring axis as center, and in these grooves are arranged anti-friction members such as balls 10. A relatively thin spacer ring 13 is disposed intermediate ring 7 and the turntable and is provided with spaced apertures receiving and maintaining balls 10 in properly spaced relation. Spacer ring 13 is preferably made up of a number of segments 13a, Figure 3, these segments being preferably joined together at their abutting ends as by welding, although they may be disposed merely in freely abutting relation.

Inwardly of groove or race 12 a number of brackets 14 are secured in depending relation to the turntable immediately within the ring, and extend substantially to the bottom of the latter. Brackets 14 are spaced on a common circle concentric with the ring axis and at their lower ends support an annulus 15 which underlies the lower face of ring 7. The upper outer margins of annulus 15 are rabbeted as shown in Figure 2, and provided with a groove 16 opposed to a groove 9 in the bottom face of ring 7, these two grooves being developed on equal radii from the ring axis, and engaging balls 17 between them, the balls being maintained in spaced relation by means of the spacing ring 18 similar to spacing ring 13 above described.

Balls 10 transmit the weight of the turntable to ring 7 and are retained in their races due to the engagement of the lower face of the ring by annulus 15 through the intermediary of balls 17, the latter preventing tilting of the turntable relative to the ring. Due to the secure engagement of both sets of balls within their races, they act to prevent radial displacement of the turntable relative to the supporting ring.

Due to the above provisions, the turntable is supported for free rotation relative to the supporting ring while at the same time its bodily movement relative to the latter is effectively prevented. As sliding friction of the supporting and guiding elements is practically eliminated, there is less requirement for lubrication and attention than in the old construction.

While the upper and lower races of ring 7 and the upper turntable race are shown as being

126

formed directly in those members, it is obvious that they might be formed in separate annular elements secured in proper relation to the parts.

Although I have described a specific embodiment of my invention, it will be understood that I do not limit myself to structure except as set forth in the following claims.

I claim:

- 10 1. In a mining machine, a support, a substantially horizontal ring mounted on said support, a turntable having a circular portion overlying the upper face of the ring, a horizontally projecting cutter bar mounted on the turntable, means for swinging the turntable relative to the ring, balls 15 interposed between said circular portion and said upper face to support the turntable for rotation relative to the ring, a plurality of circumferentially spaced brackets depending from and bolted to the turntable, an annular member bolted to 20 and supported by said brackets in underlying relation to the lower face of said ring, and balls engaged between the lower face of the ring and

said annular member to prevent tilting of the turntable relative to the ring.

2. In a mining machine, a support, a substantially horizontal ring above said support and having its top and bottom faces provided with continuous grooves, means between the support and ring adjustable to adjust the ring translationally relative to the support or to tilt it relative to the latter, a turntable having a circular portion overlying the upper face of the ring and a circular portion underlying the lower face of the ring and means rigidly connecting said circular portions, a horizontally projecting cutter bar mounted on the turntable, means for swinging the turntable relative to the ring, said circular portions being provided with grooves opposed to and registering with the top and bottom grooves of said ring, and balls in said grooves to support the turntable for rotation relative to the ring and to prevent tilting and radial displacement relative to the ring.

ERNST F. MULLER.
